UNITED STATES PATENT OFFICE.

THOMAS S. PEARSON AND THEODORE M. CONNER, OF KOKOMO, INDIANA, ASSIGNEES
OF ONE-THIRD TO JOHN B. DOUGAN, OF RICHMOND, INDIANA.

BALE-TIE.

1,085,938.

Specification of Letters Patent. Patented Feb. 3, 1914.

Application filed August 19, 1912. Serial No. 715,840.

To all whom it may concern:

Be it known that we, THOMAS S. PEARSON and THEODORE M. CONNER, both citizens of the United States, residing at Kokomo, in 5 the county of Howard, and in the State of Indiana, have invented certain new and useful Improvements in Bale-Ties, of which the following is a full, clear, and comprehensive specification, being such as will enable others to make and use the same with absolute exactitude.

Our present invention relates to ties to be formed of wire or other suitable material, same being more particularly intended for 15 connecting the two ends of a wire which encircles a bale of material, such as hay or straw, which is being formed in a suitable machine invented by us and which forms the subject matter of another application not yet 20 presented to the Patent Office.

The object of our invention is to form a tie of the end portions of a wire, which will be neat and attractive in appearance, strong and durable in construction and simple in 25 formation, same being adapted to be formed while the wire is under tension, and also being adapted to yield to a certain extent after the tension has been released.

A more particular object is to provide a 30 bale-tie adapted to be formed automatically by machinery; to provide a tie or knot adapted to be formed of the two ends of a wire and while the wire is under tension; and to provide a tie which is adapted to 35 adjust itself and equalize the tension after the tensioning means have been released.

Other minor objects and particular advantages of our invention will be apparent from an inspection of the accompanying 40 drawings and the specification relating thereto.

The manner of the construction of our invention is shown in the accompanying drawings, in which—

45 Figure 1 shows the two end portions of a wire from which we propose to form a tie. Fig. 2 shows a wire shaped to surround a bale, the tie being shown as having just been released from the bale. And Fig. 3 shows a wire shaped to surround a bale, the tie having 50 been completed and the pressure having been released, and showing the tie as having assumed its final position, or nearly so.

55 Similar indices denote like parts through-

out the several views of the one sheet of drawings.

In order that the formation and the advantages of our invention may be more fully understood and appreciated we will now 60 take up a detailed description thereof in which we will set forth the invention as briefly and as comprehensively as we may.

In the drawings A denotes the body or central portion of a length of wire surrounding, or adapted to surround, a bale.

B and C denote the termini of the wire A, there being a surplus end-portion adjoining each of the termini, from which latter the tie proper is formulated. In practice the 70 wire is placed tightly around a bale by machinery and while the bale is still under great pressure, and the wire under tension, the tie is formed automatically by the machine. The tie is formed near one corner of 75 and it first extends at right angles to the longer side thereof, as in Fig. 2.

The tie is formed by first making a double loop, that is forming a loop of part of each surplus end portion of the wire, the two 80 surplus end portions having first been brought parallel to each other as in Fig. 1, and the two loops are formed at one time and are complements of each other. The unused parts of the end portions of the wire, that is 85 the parts remaining between the loops and the termini, are then tightly twisted helically together around the end portions of the wire between the loops and the portions of the main body A of the wire which extend over the end of the side of the bale, thereby forming the tie as shown in Fig. 2, which at this 90 time is a yielding tie, that is it is adapted to yield to a limited extent when under great or surplus pressure. After the pressure is released from the press holding the bale and the wire, then the expansive force will cause the tie to contort from its original form shown in Fig. 2 to the position shown in Fig. 3, 95 wherein the pressure of the bale has been allowed to adjust itself. From the above it is apparent that the tie is capable of self adjustment, equalizing the pressure. Otherwise, that is if the tie were formed rigid and non-expansile the wire might be broken but by forming a limited expansive tie we provide means whereby the pressure on all the wires and the ties will be substantially uniform under all conditions.

Having now fully shown and described 110

our invention, what we claim and desire to secure by Letters Patent of the United States, is—

A yieldable bale-tie, comprising in combination, a single length of wire having a body portion to surround a bale, the surplus end portions of the wire laid parallel with each other and formed into a double loop, the parallel end portions, after said loop is formed, being coiled around the double portions of the wire between the loops and the body of the wire which surrounds the bale, said loops and coils being wholly outside the body of the wire which surrounds the bale,

the said loops being adapted to decrease in size by the expansive force of the bale exerted upon the body of the wire after the tie is formed, all substantially as shown and described.

In testimony whereof we have hereunto subscribed our names to this specification in the presence of two subscribing witnesses.

THOMAS S. PEARSON.
THEODORE M. CONNER.
